APPLIQUE EMBLEM

Shirley Bellmon, Billings, Okla. 74630

Filed Oct. 18, 1967, Ser. No. 9,047

Term of patent 14 years

U.S. Cl. D3—9
Int. Cl. D5—07

In the drawing, the single figure is a face view of an applique emblem showing my new design.

The essential features of my design reside in the portion shown in solid lines. The stippled portion indicates a color contrast rather than any specific color.

I claim:

The ornamental design for an applique emblem, substantially as shown and described.
